UNITED STATES PATENT OFFICE.

JAMES H. VANN, OF PHILADELPHIA, PENNSYLVANIA.

LATH-NAILING MACHINE.

Application filed May 11, 1926. Serial No. 108,442.

My invention relates to new and useful improvements in a lath nailing machine, and has for its primary object to provide a semi-automatic machine for nailing laths 5 to wall studding in either vertical or horizontal positions, the latter being generally known as joists for ceiling and floor.

Another object of the invention is to construct such a machine in two main parts, 10 one of which is detachable from the other, said detachable portion being used only when nailing overhead.

A further object of the invention is to provide a spring actuated hammer of unique 15 construction.

A still further object of the invention is to provide a simple and effective means for actuating several of the hammers in unison.

With these ends in view, this invention 20 consists in the details of construction and combination of elements hereinafter set forth and then specifically designated by the claims.

In order that those skilled in the art to 25 which this invention appertains, may understand how to make and use the same, I will describe its construction in detail, referring by numerals to the accompanying drawings, forming a part of this application, in which:

30 Fig. 1, is a front elevation of the lath nailing machine embodying my invention with that portion used for overhead work detached.

Fig. 2, is a side elevation of the same with 35 the overhead nailing portion in place with parts being broken away, and some elements shown in section to clearly illustrate details of construction.

Fig. 3, is a top plan view of that portion 40 of the machine shown in Fig. 1, which is used in vertical or side wall nailing operations.

Fig. 4, is a plan view of the overhead nailing portion.

45 Fig. 5, is an enlarged fragmentary view of the hammer actuating mechanism, as shown in Fig. 3.

Fig. 6, is a side elevation of Fig. 5.

Fig. 7, is a section at the line 7—7 of

50 Fig. 6.

Fig. 8, is a section at the line 8—8 of Fig. 6.

Fig. 9, is a plan view of one of the hoppers.

Fig. 10, is an edge view thereof.

Fig. 11, is a vertical sectional view of the same at 11—11 of Fig. 9. Fig. 12, is a face view of the same with a portion of the hopper broken away and showing the details of the operating mechanism at the line 12—12 of Fig. 9.

In carrying out my invention as herein embodied, 15 represents a suitable frame or truck body supported by wheels or casters 16, so that the device may be readily transported from one place to another within a building, or a room thereof. On this truck or body are mounted a desirable number of elevators 17, each consisting of an inner tube 18 fixed to the body, and an outer tube 19 telescoping over the inner tube and 20 slideable relative thereto; while the interior of these tubes are in communication through passageways 20 in the partition 21 at the outer end of the inner tube.

To the upper ends of the elevators, and more particularly the outer tubes 19, is secured the platform 22, which supports suitable brackets 23 and hangers 24, and in the brackets 23 are journaled axles 25 and 26, so having sprockets 27 fixed thereon, while in the lower ends of the hangers is journaled another axle 28 having sprockets 29 fixed thereto, and further provided with a suitable operating crank 30. It is to be understood that there are two sets of the sprocket wheels just described, one set on each side of the machine, and over each set of sprockets runs a chain 31, provided with clips 32, suitably spaced and arranged with their 35 open ends opposite the direction of travel of the chain. These clips are adapted to have laths placed therein so that the laths will be carried thereby to the top of the machine and then released, as the clips pass 40 around the sprocket wheels 27 on the shaft 26.

When released, the laths will pass into and descend between the guides 33 which are made in collapsible sections, or otherwise telescopically arranged, in order that their lower ends may be maintained relative to the table 34, which will be raised or lowered by the jack screws 35 journaled

in the body 15, and having beveled gears 36 on their lower ends; said gears meshing with gears 36' on a jack shaft 38' on which is also a gear 37' meshing with the gear 37 on the shaft 38, which also has another beveled gear 39 thereon, meshing with the beveled gear 40 on the vertical shaft 41, to which is secured a crank handle 42, so that when the latter is revolved, the table will be moved vertically.

On the table are mounted a plurality of hammers 43 transversely spaced to correspond to the usual spacing of building studs and beams, and are adapted to propel lath nails into and through a lath 44 positioned in front of them and supported by rests 45, slidably mounted in suitable brackets 46, and normally forced outward by springs 47 attached to the pins carried by the rests, and when a lath is lying upon the rests, its upper edge will be below the lower end of the outermost guide member 33.

Each of the hammers 43 includes a cylindrical casing 48, having a filler 49 at its outer end with a bore 50, into which projects the percussion member 51 formed as a part of or carried by the piston 52, slidably mounted in the hammer casing and normally forced outward by a spring 53 between the piston 52 and the head 54 of the hammer casing, and in the filler 49 is a slot 55 communicating with the bore 50 as well as with a slot 56 in the hammer casing which, in turn, communicates with a slot 57 in the strap 58, and said slot 57 communicates with a slot 59 in the bottom of the magazine casing 60, while in the latter is rotatably mounted a magazine 61 provided with a plurality of spaced pockets 62 about its periphery, which successively align with the slot 59 and with the outlet 63 from the nail hopper 64. The magazine is intermittently rotated through the medium of a gear 65 on the shaft 66 of said magazine, and the gear 65 meshes with a gear 67 fixed to a shaft 68 also carrying a ratchet wheel 69, with which coacts the ratchet 70 mounted on the oscillating arm 71. This arm is actuated each time the hammer is withdrawn by means of a finger 72 on the outer end of the pin 73, which is fixed to the hammer piston and slides in a slot 74 in the hammer casing to prevent rotation of the piston.

Projecting from the piston and out of the rear end of the hammer casing is a piston rod 75 provided with a rack 76 whereby the piston may be drawn outward against the action of the spring through the medium of a rack pinion 77, rotatably mounted on a shaft 78. The rack pinion is provided with a lug 79 for coaction with the sliding bolt 80 mounted in a suitable bolt support 81, such as a disk, splined on the shaft 78 so as to rotate therewith. This bolt has a beveled nose 82 which is normally forced toward

the rack pinion, with which it is associated by a spring 83; while the rear end of the bolt is longitudinally slotted as at 84 to receive the circular bolt actuating member 85 secured by suitable means 86 to the machine table 34, the said bolt actuating means having a cam 86^a formed therewith.

On the shaft 78 is also fixed a gear 87 which meshes with a gear 88 keyed to the shaft 89 so as to revolve therewith and slide thereon. The shaft 89 has a beveled gear 90 fixed thereon and meshing with a beveled gear 91 fixed to the bearing portion 92 of the treadle 93.

It is to be understood that there are as many rack pinions and associated parts mounted on the shaft 78 as there are hammers so that each time the treadle 93 is depressed, the shaft 78 will be rotated, and therefore carry each bolt supporting member 81 with it which will rotate the associated rack pinions and draw the hammer pistons outward against the action of their springs, until such time as the bolts ride upon the cams 86^a when said bolts will be drawn out of engagement with the lugs 79 on the rack pinions, thereby releasing the latter and permitting the hammer springs to propel the hammer pistons.

In order to return the treadle and its component parts to their normal positions after each operation of the hammers, a spring 94 is attached to a portion of the bracket 95 supporting the bearing for the gear 90, shaft 89 and treadle bearing, and to a tail piece 96 projecting from the rear of the treadle.

During the operations, the platform 22 may be raised to any desired or required height by permitting air to pass through the supply pipe 95^a from any suitable source of supply which is controlled by a valve 96^a, and then through the branch pipes 97 into the several elevators 17, where the air will pass through the openings 20 and act upon the cylinder 19 and the partition 21 of each elevator causing the outer cylinders to fly over the inner ones, thereby moving the platform upward.

Next, the conveyor is caused to travel by revolving the crank 30 and laths are placed in the clips 32, and as said laths reach the outer ends of the guides 33, said laths will be released and drop down between the guides 33 and come to a stop upon the rests 45 directly in front of the hammers. As soon as a lath has fallen upon the rests, the treadle 93 is depressed, which will draw back the hammer plunger and simultaneously rotate the magazine 61 until a pocket with a nail therein aligns with the slots leading to the bore of the hammer filler so that the nail in said pocket may drop in front of the percussion member 51, so that when released, said percussion member will drive the nail through the lath and into the stud. As there are a

number of these hammers working simultaneously the entire lath will be nailed in place at one time. During these operations another pocket of the magazine 61 will have 5 moved into alignment with the outlet 63 of the hopper 64 so that a nail from said hopper will enter said pocket, thereby keeping a continuous supply of nails in readiness for the operations of the hammer.

10 As soon as one lath has been nailed in place, the handle 42 is given a partial or complete turn, according to the ratio of the several gears connected therewith, it, through the screws 35, will elevate the table 34 there- 15 by raising the hammers to the position for nailing the succeeding lath.

So far the description has related entirely to the structure and operations for nailing laths to vertically arranged studding, and 20 in order to utilize this same machine for nailing laths on horizontally arranged studding, as for ceiling work, I provide an auxiliary detachable frame 100, which may be braced by suitable struts 101, and in each 25 end of this frame are journalled shafts 102, each provided with a pair of sprocket wheels 103, over which run suitable chains 104, provided with spaced dogs 105 to convey laths released from the clips 32 along frame 30 100 until properly positioned for nailing. These conveyor chains are operated through the medium of a drive chain 106 passing over a sprocket 107 on the shaft 26 of the main frame of the machine and over 35 sprocket 108 on one of the shafts 102.

On the frame is slidably mounted a hammer carriage 109, supporting a number of hammers 110, which are similar to the hammers 43 hereinbefore described, and which 40 are operated in a similar manner except that instead of a treadle, a hand actuating mechanism or stirrup is provided because of the varying height of the hammers, due to elevation of the platform 22. The hammer carriage is moved back and forth along the frame 100 by means of screw threaded rods 111, one of which may be operated through 45 the medium of a flexible shaft or its equivalent (not shown) which may be connected with the coupling 112, attached to one of the screw threaded rods while motion is 50 transmitted to the other one through a sprocket 113, a chain 114 and another sprocket 115, the sprockets being fixed to 55 the two screw threaded rods.

In using the ceiling portion of the machine, laths with nails stuck in them are placed in the clips 32 and conveyed to the top of the main portion of the machine, 60 where they are released and therefore transferred to the conveyor chains on the auxiliary frame which will carry the laths toward the outer end of said auxiliary frame. When the laths are properly positioned, 65 the hammer carriage is then intermittently

moved along the auxiliary frame, and as the hammers pass beneath each succeeding lath, said hammers are operated so as to lift the laths and drive the nails into the studding overhead, and after such laths have been secured in place, the machine is transported 70 to another part of the room and the operations repeated.

Of course I do not wish to be limited to the exact details of construction as herein 75 shown as these may be varied within the limits of the appended claims without departing from the spirit of my invention.

Having thus fully described my invention, what I claim as new and useful is: 80

1. A lath nailing machine including a wheel supported body, a platform, means connected with the body and platform whereby the latter may be moved vertically; a table; means to move said table vertically 85 between the body and platform; hammers mounted on the table, mechanism for actuating said hammers; means for conveying laths to and across the platform; and guides to guide the laths released from the 90 conveyor means to a position in front of the hammers.

2. The structure set forth in claim 1 in connection with an auxiliary frame; means for conveying laths along said frame after 95 being released from the first conveyor means; hammers movable along the auxiliary frame; means to move said hammers; and means to actuate said hammers.

3. A lath nailing machine including a 100 body supported on wheels; elevators on said body; means for conveying air to said elevators; a platform on the elevators to be moved vertically thereby; lath conveying means to carry laths to and over the platform; jack screws supported by the body; means to revolve said jack screws; a table movable vertically through the medium of 105 said jack screws; hammers on the table; means to actuate said hammers; and means 110 to guide laths released from the conveyor to a position in front of the hammers.

4. In a lath nailing machine, a plurality 115 of hammers, each including a piston element; racks connected with the piston elements; a shaft; rack pinions loosely journalled on said shaft and meshing with the racks; bolt supporting means fixed to said shaft; bolts slidably mounted in said supporting means for coaction with lugs on the rack pinions; 120 springs normally holding the bolts in engagement with said lugs; fixed bolt supporting means passing through longitudinal slots in the bolts and having cams thereon; a gear on said shaft; a vertical shaft at right angles 125 to the first named shaft; a gear splined for rotation with and slidable movement on the second named gear and meshing with the gear on the first named shaft; a treadle; a gear connected with the treadle; another 130

gear on the second named shaft and meshing with the treadle gear; and means to normally hold the treadle in the position for operation.

5. The structure set forth in claim 4 in connection with hoppers to hold nails and magazines to receive nails from the hoppers

and deliver them to the hammers; said magazines being operated each time the hammers are actuated.

10

In testimony whereof, I have hereunto affixed my signature.

JAMES H. VANN.
